FUME HOOD

Herman P. Angermueller, Cranford, N. J., assignor to Allied Chemical & Dye Corporation, New York, N. Y., a corporation of New York

Application September 4, 1947, Serial No. 772,173

3 Claims. (Cl. 98—36)

1

This invention relates to a fume hood for laboratory or other uses in which hazardous chemical reactions may be carried out, and heat, dust, toxic and odoriferous vapors and gases removed, thereby providing sanitary, safe and healthy working conditions for personnel, and to novel processes of ventilating such hoods.

Fume hoods heretofore available usually consist of a cabinet having a fixed or sliding window or door controlled service opening, which cabinet communicates with an exhaust fan for removal of the objectionable dust, vapors and gases generated within the hood. Of these two types of fume hoods the type involving the adjustable or sliding service door controlled service opening has been found to be superior. However, such fume hoods have certain vital objections. Thus, for example, in such fume hoods, the removal of dust and toxic or odoriferous gases is effected by an exhaust fan drawing in a surplus amount of air from the room in which the fume hood is disposed through the service opening, which air circulates across the base of the hood to effect ventilation of this portion of the hood and remove relatively heavy gases and vapors and also through the upper portion of the hood to effect removal of the lighter gases and vapors. In the operation of these fume hoods it has been found invariably to be the practice that the adjustable door controlling the extent of the service opening is usually lowered only when excessive amounts of gases or odoriferous substance are generated and then the door is almost completely closed. When the door is thus positioned, the hood does not properly perform its ventilating function because of the lack of entering air, and this, it will be noted, takes place under conditions when a large excess of air is essential to effect the removal of the excessive amount of gases or odoriferous substances produced within the hood.

Another serious objection to such fume hoods is that the air required for ventilation is taken from the room in which the fume hood is disposed. Thus, dependent upon size and number of hoods in operation, considerable heat losses are necessarily entailed when the room is heated. When windows or doors in the room containing the hood are open, unfiltered outside air is drawn into the room thereby depositing considerable dust in the laboratory or other room in which the fume hood is disposed and also on the equipment in this room. This objectionable dust deposit also takes place even though the windows and doors of the room are closed due to the fact

that unfiltered outside air is drawn in through existing cracks or other leaky spaces in the room.

The above noted objection is particularly acute in those cases where the fume hoods are used in air conditioned rooms. Air conditioning is becoming more and more prevalent in laboratories and research institutions not only to improve the comfort of personnel but to provide dust-free and uniform operating conditions which are essential for the proper handling of many materials and instruments employed in modern research. When existing fume hoods are employed in air conditioned rooms not only do such hoods, depending upon their size and number in operation, rob the room of large amounts of costly conditioned air, but the widely varying quantities withdrawn from the room, apart from the cost factor, render it extremely difficult to maintain satisfactory operating conditions in the air conditioning system.

Among the objects of this invention is to provide a fume hood which can with equal performance be used in an air conditioned or non-air conditioned room, which when used in an air conditioned room will not materially affect the air conditioning system by taking air from the room, which may be ventilated uniformly and thoroughly and this independently of the position of the door controlling the service opening, in which the ventilating air supply can be easily adjusted to insure removal of heavy gases and which can be easily converted from a fume hood having a support for equipment at "table" level to a hood of a height corresponding to that of the room enabling the installation within the hood of tall or heavy equipment at a level substantially the same as the level of the floor of the room in which the hood is disposed.

Other objects and advantages of this invention will be apparent from the following detailed description thereof.

In accordance with this invention, a fume hood having a service opening is ventilated by flowing a stream of air across this opening so as to produce a flowing curtain of air, minimizing the entry of air from the room in which the hood is disposed into the hood, the air passing through the hood to thoroughly ventilate it. The preferred construction involves a housing defining a fume chamber having a service opening in its face, an air supply channel above said chamber leading into a duct which extends across said opening and through which air flows to produce the flowing curtain of air extending across substantially the full area of the service opening, thereby minimizing the entry of air from the

room in which the hood is disposed into the fume chamber, a fan for supplying air to the air supply channel, an exhaust channel also disposed above the fume chamber and communicably connected with the top of the fume chamber, an exhaust duct leading from the exhaust channel to the base of the fume chamber, an exhaust fan connected with the exhaust channel and a damper in the connection between the exhaust channel and the top of the fume chamber to regulate the relative proportions of air passing from the air supply channel across the base of the fume chamber into the exhaust duct and passing through the upper portion of the fume chamber into the exhaust channel.

Desirably the fume chamber is provided with openings in side wall ducts connected with the air supply channel so that air sweeps into this fume chamber not only in a downward direction forming a curtain extending substantially completely across the face of the service opening but also from the side walls of the fume chamber to produce flowing side streams of air merging with the front stream, the resultant air stream flowing towards the rear of the fume chamber across the base and upwardly through the top portion of the fume chamber. These side streams co-operate with the front or downwardly flowing stream to minimize the entry of atmospheric air from the room in which the fume hood is disposed into the fume chamber.

In the preferred embodiment a removable floor is disposed in the fume chamber to provide a support for equipment at the usual "table" level. Upon removal of this floor a fume chamber is provided of a height which, if desired, is substantially equal to that of the room in which the fume hood is disposed. Tall or heavy equipment may be readily positioned in this chamber, the floor of which desirably is the same as that of the room in which the fume hood is positioned.

In the accompanying drawings forming a part of this specification and showing for purposes of exemplification preferred forms of this invention without limiting the claimed invention to such illustrative instances:

Figure 1 is a front elevational view of a fume hood embodying this invention;

Figure 2 is a vertical section taken in a plane passing through line 2-2 on Figure 1;

Figure 3 is a horizontal section partly in elevation, taken in planes indicated by lines 3-3 on Figure 2;

Figure 4 is a vertical section, on an enlarged scale, as compared with the scale of Figures 1 to 3, inclusive, taken in a plane passing through line 4-4 of Figure 2;

Figure 5 is a fragmentary plan view, on a still larger scale, showing one form of damper mechanism for regulating the opening connecting the upper part of the fume chamber with the exhaust duct, viewing this mechanism from the direction indicated by the arrows 5-5 on Figure 2;

Figure 6 is a vertical section taken in a plane passing through line 6-6 of Figure 5;

Figure 7 is a front elevational view of a fume hood embodying a modified form of this invention; and

Figure 8 is a vertical section taken in a plane passing through line 8-8 of Figure 7.

Referring to the drawings, 10 is a fume hood, desirably in the form of a rectangular cabinet having corner posts 11, suitably braced by cross pieces and angle irons 12. A rear wall 13 and

side walls 14 and 15 extend from the level of the floor of the room in which the fume hood may be disposed to the top of the hood, these walls being imperforate, thus completely enclosing the hood on three sides. Side wall 14 and 15 are suitably secured to the corner posts: one or more tie rods 16 pass between structural members such as angle irons secured to these side walls as shown in Figures 2, 3 and 4. A cover plate 17 closes the top of the hood. A front plate 18 extends from the cover plate 17 to a point 19 spaced from a removable floor 20, forming a service opening 21, desirably of rectangular shape. A door 22 having a window 23 which may be of glass or other transparent material, is slidably mounted so that it can completely or partially close the service opening 21.

Any desired mounting for door 22 may be employed. For example, the door may be suspended by a pair of wires or ropes 23', each having a counterweight 24 at one end, passing over a pulley 25 and both having the other end fastened to the top of the door as at 26 and 27. The door is thus mounted for sliding movement just in front of plate 18; when in its upper position shown in Figures 1 and 2, its lower edge is flush with point 19, leaving the service opening completely unobstructed. It may be moved to any desired position, regulating the extent of opening of the service opening 21 and remaining in the position to which it is moved.

A fume chamber is formed within the fume hood by an interior back wall 28 spaced from the rear wall 13 to produce an exhaust duct 29 leading into the base of the fume chamber through a series of openings 30 in wall 28. The sides of this fume chamber are defined by side walls 31, 32 spaced respectively from the side walls 14, 15 to produce side wall air ducts 33, 34, respectively. Each of the side walls 31, 32 has a series of elongated openings 35 through which the air ducts 33, 34 communicate with the fume chamber. Openings 35 are of suitable size and shape to uniformly distribute the air along the length of the side walls. They may be of the shape shown in Figure 2 and are positioned in the side walls near the front of the fume chamber. Stud bolts 36, provided with wing nuts 37, are positioned just above and below each of these openings for receiving cover plates for blanking off the openings 35 when it is desired so to do. The base of this fume chamber is defined by removable floor 20 which rests on the cross pieces 38 extending along the base of the inner side walls 31, 32 and is suitably fastened thereto.

The top of the fume chamber is defined by a plate 39 spaced from the top plate 17 and inclined downwardly from wall 28 toward the service opening 21. A partition 40 extends parallel to the rear wall 13 spaced therefrom to provide in the upper portion of the fume hood just above the fume chamber an exhaust channel 41 and an air supply channel 42. Communicating with the lower portion of the air supply channel 42 extending across substantially the full face of the fume chamber is an air supply duct 43 which may be formed by extending the top plate 39 defining the top of the fume chamber in a downward direction to produce extending wall 44 parallel with front plate 18.

An exchangeable bar 43', desirably of wood, and of a length equal to that of the air supply duct 43 is disposed within duct 43 contiguous to wall 44. Thus by inserting a bar 43' of proper thickness in duct 43, the effective outlet width of this

duct is controlled to give the desired air outlet velocity therethrough. Disposed just above the top of bar 43' in wall 44 is a series of spaced openings 44' which may be equi-spaced and extend along the full length of duct 43. Air flows through these openings directly to the corner defined by plate 39 and wall 44 to ventilate this corner and avoid the formation of a vacuum therein by the relatively high velocity streams flowing through side wall openings 35 and duct 43.

The air supply channel 42 has at its opposite ends openings 45, 46 (Figure 4) communicating with the air supply ducts 33, 34. Flow through openings 45, 46 into the air supply ducts 33, 34 may be controlled or regulated by dampers 45' and 46' (Figure 4), respectively. An air supply conduit 47 extends into the top portion of air channel 42, desirably midway between the ends thereof. Conduit 47 communicates with a motor-driven fan or blower 48 of any conventional type which is provided with an air supply conduit 49 leading to an air supply duct or to the atmosphere exterior of the building in which the fume hood may be positioned so that, if desired, air is supplied under pressure to the air channel 42 from a source other than that of the room in which the fume hood is disposed.

The exhaust duct 29 leads into the exhaust channel 41 at 50. A conduit 51 leads from one side wall of exhaust channel 41 to a suitable exhaust fan of any conventional type indicated diagrammatically at 52. This fan draws the exhaust products from the fume chamber and discharges them into a chimney flue or directly to the atmosphere or other suitable disposal point.

Plate 39 defining the base of the exhaust channel 41, as shown in Figures 2, 3 and 5 is provided with a series of spaced rectangular openings 53 extending in substantially equi-spaced relation the full length of this exhaust channel. Cooperating with these openings is a sliding damper plate 54 (Figures 5 and 6) having spaced openings 55 therein separated by intervening imperforate plate portions 56. Hence, depending upon the position of the sliding plate 54, the openings 53 may be completely closed or left open to any desired extent. Plate 54 is mounted for sliding movement in a pair of guides 57, 58 suitably bolted or otherwise suitably secured to plate 39.

Movement of plate 54 may be effected by any suitable mechanism. For example, this plate may have fixed thereto one end of a rod 59 as by welding. The other end of this rod is threaded and passes through a threaded nut 60 keyed or integrally formed within a beveled gear 61 mounted for rotation in a bearing support 62 secured to the side wall 15. A beveled gear 63 meshes with gear 61; gear 63 is keyed to a shaft 64 rotatably mounted in bearings 65 on the side wall 15. A hand wheel 66 is fixed to shaft 64 for effecting its rotation.

Mounted on the back wall 28 of the fume chamber is a series of lines 67 which extend through side walls 14 and 31 and terminate within the fume chamber. These lines provide sources of suitable media which may be required in the operation of the equipment placed within the fume chamber; thus, for example, there may be a steam line, power line, compressed air line, warm and cold water lines, vacuum line, fuel gas line, etc. The rear of the fume chamber is provided with a lead lined drainage trough 68 communicating with a drain line 69 leading to any suitable disposal point.

Removable floor 20 desirably is positioned about 3 feet above the floor of the room in which the fume hood is disposed so that it provides a support for equipment at a height which permits convenient placing of equipment thereon, i. e., at usual "table" level. When it is desired to place tall or heavy equipment within the fume chamber, removable floor 20 may be slid from its supports 38 thereby providing a fume chamber of room height having the rear and both sides completely enclosed and having an opening in the face extending from point 19 to the floor of the room in which the chamber is positioned.

The modification of Figures 7 and 8 differs from that hereinabove described chiefly in that the exhaust fan is mounted on the top of the fume hood and not on a side wall as shown in Figures 1, 2, and 4. Parts in Figures 7 and 8 corresponding to those of Figures 1, 3 and 4 have been given like reference characters. In Figures 7 and 8, 71 indicates an exhaust fan mounted on the top of the fume hood and communicating with exhaust channel 41. The exhaust fan 71 discharges into a conduit 72 leading into a stack 73. The exhaust fan 71 of Figures 7 and 8 and 52 of Figures 1 and 4 should be of sufficient capacity to exhaust the volume of air supplied by the air supply fan 48 plus the gases liberated in the fume hood taking into account increased volumes due to heating of the air which may take place in its flow through the hood. The placement of the exhaust fan contiguous to the air supply fan, as shown in Figures 7 and 8, is preferred in the interests of simplicity and compactness; the exhaust fan, however, may be placed on either side of the hood, or even on the back of the hood, if desired. Also the air supply fan may be positioned at any convenient point for supplying air to the air supply channel 42.

In operation, all the air required for ventilating the hood is delivered by the fan 48 equipped with a discharge damper (not shown) for controlling flow of the air stream into air supply channel 42. The air thus supplied flows through side wall openings 45, 46 into the air supply ducts 33, 34 through the openings 35, as indicated by the arrows on Figure 4. Air also flows through the duct 43 extending across the full face of the fume chamber producing a curtain of air which flows downwardly covering substantially the entire area of the service opening 21 and minimizing the entry of air from the room in which the fume hood is disposed into the fume chamber.

Adjustable damper plate 54 regulates the amount of the air thus supplied flowing through the upper portion of the fume chamber through openings 53 into the exhaust channel 41 relative to that flowing across the base of the fume chamber through openings 30 into the exhaust duct 29 and thence into the exhaust channel 41. When the damper plate 54 is positioned so that openings 53 are completely unobstructed, approximately 50% of the total air introduced into the fume chamber by fan 48 flows through the openings 53 into exhaust channel 41 and the remainder of the air across the base of the fume chamber into and through the base openings 30 leading into the exhaust duct 29. If equipment generating large amounts of heavy gases, i. e., heavier than air, is disposed within the fume chamber, hand wheel 66 is actuated to move plate 54 to partially or completely close openings 53 so that more or all of the air respectively will flow over and across 75, table top 20 leaving through slots 30 and thereby

effectively ventilating the base of the fume chamber.

When employing the hood as a relatively high chamber, i. e., when the hood is used with the floor 20 removed, and it is desired to more extensively ventilate the floor of the hood, the side wall openings 35 may be blanked off completely by mounting the cover plates on the stud bolts 36 or the air stream flowing through channels 33, 34 may be reduced by suitably positioning dampers 45' and 46'. Also, the door 22 should be fully lowered. Under these conditions all or most of the air supplied by fan 48 is delivered at a high outlet velocity through the duct 43, forming a curtain of air extending substantially entirely across the full area of the open portion of the hood.

When designing a hood for use exclusively with heavy or high equipment intended to be mounted at the room floor level, the exhaust openings 30 are desirably placed in a lower position than that shown in the drawings, for example, they may be placed just above the floor level leading into a rear duct communicating with the exhaust channel 41.

In the fume chamber of this invention, it should be noted the counterbalanced door does not function to control the air introduced into the fume chamber but chiefly to protect the operator against splashing or leaks of gas or vapor from the equipment installed under the hood. The ventilation of the hood is independent of the position of the sliding door and is optimum when the door is fully closed.

It should be further noted the hood of this invention, with equal performance, can be used in air-conditioned as well as non air-conditioned laboratories or other rooms without detrimental effect upon the atmospheric conditions of the room in which it is placed. Since little or no air is taken from this room, heat losses during the winter time are negligible. If installed in an air-conditioned room, loss of more costly conditioned room air is likewise negligible. Unfiltered outside air containing the usual amounts of dust and bacteria are not caused to enter into the room in which the fume hood is disposed, thereby eliminating precipitation of dust and dirt in the room and upon the equipment and personnel therewithin.

Air filtered or unfiltered and tempered as may be desired is supplied by means of the fan 48 to the fume chamber at uninterrupted controlled velocity. When installing a plurality of fume hoods embodying this invention in a building, all of the hoods may obtain their air supply from a common main air duct, which may contain filtered, preheated or otherwise tempered air serving as supply medium for one or more hood fans communicating with such main air duct. Similarly, one or more exhaust fans may be connected to a common main exhaust duct communicably connected with the exhaust channels 41 of all or several fume hoods.

By regulating the extent of damper openings 53, the direction of air flow through the fume chamber is adjusted to effect most efficient removal of heavy and light gases. By removing floor 20, the hood may readily be converted from a hood having a floor at usual "table" level to a hood room in which heavy or tall equipment may be installed at room floor level.

If, for any reason, it is desired to use the hood for removal of air from the room in which the hood is disposed, say in lieu of other ventilating

facilities, it is only necessary to shut off air supply fan or blower 48, in which case the exhaust fan 52 will serve to draw in air into the fume chamber from the room in which the hood is disposed.

The fume hood may be made of any suitable materials of construction. Dry seasoned wood is preferred for structural members, such as corner posts, spacers, crosspieces, etc., all of which come in contact with the exhaust fumes. Metal may be used for the supply air portion of the hood.

Transite, asbestosite, treated plywood or similar materials may be used for walls, partitions, channels and ducts of the hood. As is well known 15 "transite" and "asbestosite" are Portland cement asbestos compositions usually in board or sheet form.

Suitable surface protecting coats applied by spraying or painting parts constructed of wood, 20 metal or any other selected materials may be employed to protect against corrosion, contamination and deformation of such parts which are subjected to severe service conditions.

Since certain changes in the fume hood and 25 in the manner of effecting its ventilation may be made without departing from the scope of this invention, it is intended that all matter in the above description or shown in the accompanying drawings shall be interpreted as illustrative and 30 not in a limiting sense.

Thus, for example, while the service opening has been shown in front of the fume chamber, it may be disposed in either side wall or even in the top of the fume chamber and a blanket 35 or curtain of air passed thereacross into an exhaust duct to effect removal of fumes and ventilation of the chamber.

What is claimed is:

1. A fume hood comprising, in combination, a 40 housing defining a fume chamber having a service opening in the front wall thereof, an air supply channel above said chamber, a fan for supplying air to said channel, an exhaust channel also disposed above said chamber and connected with said chamber, an exhaust fan connected with said exhaust channel, an air duct extending across said service opening and communicably connected with said air supply channel for flow of air through said air duct to produce a flowing curtain of air extending substantially completely across said service opening, air ducts in the side walls of said housing communicably connected with said air supply channel for flow of air through said side wall air ducts into said fume chamber, a damper in the connection between said exhaust channel and said fume chamber, and an exhaust duct extending along the rear of said fume chamber and connecting said exhaust channel with the base portion of said fume chamber.

2. A fume hood comprising, in combination, a housing defining a fume chamber and comprising rear, side and front walls, the front wall having a service opening therein and the rear and side walls being substantially imperforate, the lower edge of said housing adapted to rest on the floor of a room in which said housing may be disposed, a removable floor for said fume chamber disposed to provide a support for equipment at 65 "table" level, the removal of said floor permitting the installation of equipment in said chamber at substantially the floor level of said room, means for producing a flowing curtain of air extending across said service opening, an exhaust channel in 70 the upper portion of said housing in communica-

tion with the upper portion of said fume chamber, and an exhaust duct leading downwardly from said exhaust channel and communicating with said fume chamber at a point in the neighborhood of said "table" level.

3. A fume hood comprising, in combination, a housing defining a fume chamber and consisting of rear, side and front walls, the front wall having an opening therein extending from the base thereof to a point short of the top of said housing and the rear and side walls being substantially imperforate, the said housing being adapted to rest on the floor of a room, a removable floor for said hood disposed approximately midway between the top and bottom of said opening to provide a support within said chamber for equipment at "table" level, removal of said floor permitting the installation of tall or heavy equipment within said chamber on the floor of said room, an air supply channel above said fume chamber, a fan for supplying air to said channel, an exhaust channel also disposed above said fume chamber and connected with said chamber, an exhaust fan connected with said exhaust channel, an air duct extending across said opening in the front wall and communicably connected with said air supply channel for flow of air through said air duct to produce a flowing curtain of air extending across said opening, air ducts in the side walls of said housing communicably connected

10

15

30

with said air supply channel for flow of air through said side wall air ducts into said fume chamber, a damper in the connection between said exhaust channel and said fume chamber, and an exhaust duct extending along the rear of said fume chamber and connecting said exhaust channel with said fume chamber at a level just above the level of said removable floor.
